LIGHTING FIXTURE

Donald W. McLennan, Seattle, Wash., assignor
to Electrical Products Associates, a corporation
of California

Application February 6, 1933, Serial No. 655,307

2 Claims. (Cl. 176—122)

This invention relates to electric illumination and more particularly to gaseous glow or arc lamps applied to interior illuminating purposes, such as for show case or show window lighting.

- 5 Explanatory to the present invention it will here be stated that electrical illumination by means of gaseous filament tubes is very desirable and advantageous for certain purposes such, for example, as show window and shoe case lighting. 10 However, gaseous glow lamps, arc lamps or other lamps wherein an electric discharge is conducted, for illuminating purposes, through a column of suitable gas or vapor, such as neon or mercury vapor, produce a certain corona discharge, or a 15 certain capacity effect which has the undesirable result of creating ozone and this is very detrimental to the preservation of perishable products such as meat and vegetables, which may be in the vicinity of the ozone.
- 20 Therefore, it has been the object of this invention to provide means in connection with lamps of the above character whereby the creation of ozone is prevented and its detrimental effects eliminated. More specifically stated, the present invention resides in the provision of a transparent, gas tight enclosure entirely about the luminous tube, or tubes, providing an enclosing chamber therefor filled with an inert gas which precludes the formation of ozone.
- 25 Other objects reside in the details of construction, combination of parts and method employed, as will hereinafter be fully described.

In accomplishing these and other objects of the invention, I have provided the improved details of construction the preferred forms of which are illustrated in the accompanying drawing, wherein—

- 30 Fig. 1 is a longitudinal section of a lamp embodying the present invention.
- 40 Fig. 2 is a cross sectional view of the same. In its present embodiment, I have illustrated the lamp as composed of four luminous tubes arranged within an enclosing tube, but it is to be explained that I do not confine the lamp to any particular number or arrangement of tubes since it may consist of one or more; it being more desirable to use two or more tubes as this permits use of such colors that will be the most effective for any particular lighting purpose.

- 50 Referring more in detail to the drawing— 1, 2, 3 and 4 designate what may be illuminating tubes of the usual form, herein arranged in parallel, slightly spaced relation and each consisting of a transparent, gas tight envelope, filled with a suitable gas such as neon, argon or mercury vapor, and equipped at its opposite ends with terminal electrodes 5 and 6 and sealed in circuit connections 7 through which electrical potential may be impressed on the electrodes to cause illumination 55 of the lamp.

As herein shown the tubes are connected in series by connecting the outer end terminals of tubes 1 and 2 with the terminal at the corresponding end of tubes 3 and 4, respectively, and by connecting the inner end terminals of tubes 2 and 3; these connections being shown at 8, 8a and 8b in Fig. 1.

Should these tubes be operated while exposed to air, there would be a certain capacity discharge therefrom which, by reason of there being oxygen in the surrounding air, would create a certain amount of ozone which is extremely detrimental to the preservation of products of a perishable nature, such for instance as meats or vegetables.

To overcome this formation of ozone and its undesirable results, I enclose the entire series of tubes and their connecting and terminal portions in a transparent envelope or tube 10 leaving a chamber 11 between them and tube 10 which is first exhausted of all air or gas and is then filled with nitrogen, or any other suitable inert gas.

The circuit connections 12 and 13 for the series of lamps lead to the terminals of tubes 1 and 4 through an insulating closure member, or plug 14 sealed in the end of tube 10 and exhaustion of tube 10 is effected through a glass tube 15 in the plug which, after exhaustion, is sealed off.

It is manifest then that since the formation of ozone is dependent upon the presence of oxygen, and since the several tubes 1, 2, 3 and 4 are now entirely enveloped in a gas not containing any oxygen, the capacity effect will not operate to form ozone.

The lamp shown is only one form of design that may be used and this form was selected only for the purpose of illustrating the invention and it is not intended that the claims shall in any way be restricted to the design, size or shape of the lamp but shall be given an interpretation that is commensurate with the scope of the invention disclosed.

Having thus described my invention, what I claim as new therein and desire to secure by Letters Patent is—

1. A lamp of the character described comprising a plurality of tubular gas filled envelopes in coextensive relation with terminal electrodes on which electrical potential is impressed to illuminate the lamp and a transparent envelope enclosing all of said tubes and filled with an inert gas.

2. A lamp of the character described comprising a series of transparent gas filled envelopes, each with terminal electrodes on which electrical potential is impressed to illuminate the lamp, means connecting certain of the electrodes to join the tubes in a series circuit connection, and a transparent envelope sealed about said tubes and filled with an inert gas.
